DIE ROLL

Edward A. Weidenmiller, Chicago, Ill.

Application May 22, 1940, Serial No. 336,553

9 Claims. (Cl. 107—8)

The invention relates generally to cylindrical die rolls of the character employed in rotary cookie molding machines, and more particularly it relates to such die rolls wherein the individual die cavities are formed on a plurality of separately formed or cast segments which are then assembled to produce the desired cylindrical die roll.

The primary object of the present invention is to produce a die roll of this character which is accurate and economical of construction, and rugged in use.

When such segment-type die rolls are used for molding cookies, it is essential that the joints between the segments have a tight fit so as to prevent passage of grease or shortening from the cookie dough into the interior of the die roll.

An important object, therefore, of the present invention is to provide such a die roll wherein this desired sealing of the joints between the segments is attained by simple means which does not involve the use of additional parts.

In the use of a die roll in a rotary cookie machine it is necessary that the excess dough be removed from the die roll and from the bottom or exposed surface of the molded cookie blanks and for this purpose a scraper or knife bears constantly against the rapidly rotating die roll with a yielding pressure. With prior segment type die rolls this knife has tended to catch upon the joints between adjacent ends of the die segments. This action has been objectionable from the standpoint of noise, and by its constant impact, with even a few of these joints of a roll, has caused gradual loosening of all of the joints of the roll, as well as vibration in the machine as a whole.

A further object is to produce a segment type die roll wherein this objectionable action is positively avoided.

Other objects and advantages will become apparent from the following description, taken in connection with the accompanying drawing, in which

Figure 1 is a side elevational view showing a rotary cookie molding machine wherein the die roll of the present invention is used.

Fig. 2 is a fragmental longitudinal cross sectional view of the die roll of the invention, taken along the line 2—2 of Fig. 1.

Fig. 3 is a fragmental transverse section of the die roll.

Fig. 4 is a perspective view of one of the die

Fig. 5 is an enlarged fragmental cross section of the rim of one of the supporting members.

For purposes of disclosure the invention is herein illustrated as embodied in a segment type die roll 10 adapted for use in a rotary cookie 5 molding machine 11. Such a machine may be constructed and operated as disclosed in my co-pending application, Serial No. 329,623, filed April 15, 1940, and as herein shown comprises a frame 12 in which the molding or die roll 10 is 10 mounted in opposition to a forcing roll 13, both of these rolls being located beneath and forming a part of the bottom of a hopper 14. When the rolls 10 and 13 are rotated in unison in opposite directions, as indicated by the arrows, dough 15 from the hopper 14 is forced into the die cavities 15 of the roll 10. As the molded cookie blanks 15' move downwardly with the roll 10, a scraper or knife 16 which acts yieldingly against the roll 10, as shown in Fig. 3, removes the excess dough 20 from the molding roll 10 and the exposed surfaces of the molded cookie blanks 15'. These finished blanks move with the roll 10 into engagement with an extracting belt 17 which withdraws the molded blanks 15' from the die cavities 25 15 and deposits them on a conveyor or pan for movement into an oven 18.

The molding or die roll 10 of the present invention has a central or axial supporting and driving shaft 20 which has a pair of disk-like end plates or members 21 and a plurality of intermediate spider members 22 carried on the shaft 20 in spaced relation so as to support a plurality of individual die segments 23 to form the cylindrical outer surface of the die roll. The die 35 segments 23 are arranged in a plurality of annular rows, with the adjacent side edges of the several rows preferably in abutment (as shown in Fig. 2), and with these annular joints supported and positioned by the several spider members 22 40 and the remote side edges of the two end rows supported and positioned by the two end members 21.

In supporting the die segments 23, the die segments and the several supporting members 21 45 and 22 are so formed and associated that the roll is effectually sealed against the entrance of shortening or grease into the interior of the roll, and this result is attained in such a manner that accuracy and permanency of positioning and sealing is assured. Thus, as shown in Fig. 2, each spider member 22 has its rim 25 formed with an outwardly facing positioning or sealing surface 26 which is cylindrical or annular in form and concentric with the axis of the shaft 20. These 55

surfaces 26 are of the same diameter on all of the spider members 22; and similar sealing and positioning surfaces 26' are formed on the adjacent edges of the end members 21.

- 5 The several die segments 23 are formed with arcuate seats or positioning surfaces 27 which face radially inwardly and are adapted to rest against the positioning surfaces 26 or 26', as shown in Figs. 2 and 4. These surfaces 27 are spaced inwardly from the outer face 28 of the segment, so as to provide side edge surfaces 29 on the segment, each of these surfaces 29 being formed so as to lie in a plane perpendicular to the central axis of the finished roll 10.
- 10 15 To hold the several annular rows of segments 23 in position on the members 21 and 22, with their surfaces 27 against surfaces 26 and 26' of the supporting members, the present invention provides means which assures tight sealing engagement of these surfaces. This means comprises a plurality of cooperating cam surfaces on the supporting members 21 and 22 and on the several segments 23 whereby endwise clamping of the end disk members 21 causes the several segments 23 to be drawn radially inwardly and to produce a firm engagement between the surfaces 26 and 27.
- 20 25 30 35 40 45 50 55 60 65 70 75

In the present instance this means comprises complementary annular cam surfaces 30 on the several supporting members 21 and 22, and segmental arcuate cam surfaces 31 on the opposite sides of each die segment 23. Each annular surface 30, as seen in cross section in Fig. 2, is disposed at an angle of about 45° with respect to the positioning surfaces 26 or 26' so as to face somewhat inwardly and in an endwise direction; and each surface 30 meets the positioning surface 26 or 26' at an edge 31. One such cam surface 30 is provided for each surface 26 or 26', so that the spider members 22 have two such surfaces 30, while the end members 21 have one such surface 30.

The cam surfaces 31 of the segments are similarly disposed at an angle of substantially 45° to their positioning surfaces 27, so that each surface 31 is disposed so as to face somewhat toward a surface 27 and slightly in an endwise direction. If desired the surfaces 31 may be formed on inwardly projecting flanges 33 along the side edges of the segments, since this construction results in a segment of relatively light weight.

When the several segments 23 are in position on the supporting members 21 and 22, with their positioning surfaces 26 and 27 in opposed relation, and their cam surfaces 30 and 31 in opposed relation, the two end members 21 are drawn toward each other by clamping means such as a plurality of tie rods 34. These rods 34 project through suitable openings in the end members 21 and in the spokes 22' of the spider members 22, and have tightening nuts 35 whereby the desired clamping action is attained.

As the endwise clamping action progresses, the cooperating cam surfaces 30 and 31 act to draw the surfaces 27 radially inwardly against the surfaces 26 or 26' thereby to produce an effective sealing relation between these surfaces. It will be understood, of course, that the relative dimensioning of the several parts is such as to permit such clamping or sealing of the surfaces 26 and 27, and that the relation of the side surfaces 29 is such that these surfaces 29 of adjacent segments will be firmly engaged at the time the radially inward clamping movement of the segments is completed. One surface 29 of the

end row of segments is drawn similarly against an annular shoulder 35' formed on the end member 21, the outer surface of the end member 21 beyond this shoulder or face 35' being formed as at 36 as a cylindrical continuation of the several outer faces 28 of the die segments. 5

The abutting end surfaces of the several die segments 23 of each annular row are also proportioned so that when the clamping is completed these end surfaces are in firm sealing abutment with each other; and in accordance with the present invention the die segments are so formed that these joints formed by their abutting ends have a favorable and advantageous cooperation with the scraper or knife 16. This 15 end is attained by forming the rear or trailing end face 37 of the die segment so that it meets the outer face 28 of the segment at a relatively acute angle, as shown in Figs. 3 and 4. The forward or leading end face 38 is oppositely formed, 20 in that it meets this outer face 28 at a substantially complementary obtuse angle, as shown in Figs. 3 and 4.

Thus when the die roll is in operation, and is rotated in engagement with the knife 16 as 25 indicated in Fig. 3, the knife edge passes from one segment to another with no appreciable jar or noise; and there can be no pounding of the joint on or against the edge of the knife as in prior segment type rolls. 30

If desired, coacting interlocking lugs 39 and 40 may be formed on the supporting members 21 and 22 and on one or more of the segments 23 of each annular row, thereby to prevent circumferential displacement of the segments during use of the roll. These lugs 39 and 40 are not required except where relatively stiff doughs are to be molded, the frictional forces induced by the clamping means 34—35 being sufficient to hold the segments in place in most instances. The several support members 21 and 22 are fixed so as to rotate with the drive shaft 20 by means such as a plurality of keys 41. 40

After the several die segments 23 have been cast or otherwise formed, with the desired die cavities 15 therein, the required machining operations may be accurately and easily performed, preferably using a plurality of reference points in the die cavity to accurately position the segments in the work holder. Thus the relation of the die cavity to the positioning surfaces 27 may be established uniformly in all of the die segments, and by the action of the cam surfaces 30 and 31 the surfaces 26 and 27 are drawn firmly together, so that the several die cavities in the finished form are uniformly related to the rotative axis of the roll. Hence when the outer face of the roll is surfaced or finished concentric to this axis, all of the die cavities are of uniform capacity, and the roll will produce cookies of uniform size and weight. 55

Since proper sealing of the joints between the segments is assured by the present construction, grease cannot enter into the interior of the roll; and this desired sealed relation is preserved throughout the life of the roll since the present invention has eliminated the jarring or hammer action of the knife upon the roll. These improved characteristics of the present invention are attained without the use of added parts, so that the cost of materials and assembly is minimized. 60

In preventing chipping of metal from the joints of the roll by the scraper or knife the present invention represents a marked improvement over 75

prior segment roll constructions. With such prior constructions the tendency of the knife has been to chip metal from the leading edge of the die segments, and this objectionable action in 5 prior rolls has become more pronounced as the joints become worn or loosened in use. With the present device, the leading edge of the die segment is formed at an obtuse angle to the outer surface of the roll, so that even if the joints 10 become loose, the knife will meet a surface which will tend to cam the knife back toward its normal relation, there being no radially related edge or surface into which the knife may cut or chip as in prior rolls.

15 Moreover, the acute-angled trailing edge of the present segment is continually pressed toward or against the complementary surface of the next adjacent segment so as to tend constantly to establish a smooth joint; and this joint is continually being urged toward a tighter and more perfectly sealed relation. Hence the necessity, which has heretofore been present, of attempting to smooth over, or seal, disrupted joints in the roll, has been eliminated. The elimination of this 25 necessity for soldering is of great importance because the presence of grease or shortening in such loose joints (as well as the grease which has penetrated within the roll through such loose joints) renders the soldering difficult, with the 30 result that such solder loosens and is deposited in the cookie dough. The presence of such solder particles, or chips of the metal of the roll, in the cookies is objectionable from a public health standpoint, and from the standpoint of possible 35 liability from the consumer, and by the present invention these hazards have been eliminated.

I claim as my invention:

1. In a cast-segment type of die roll for molding 40 cookies and like articles, the combination of a central supporting shaft, a pair of disk-like end plate members and a plurality of intermediate spider members all mounted on said central shaft concentrically therewith and in spaced relation axially of said shaft, each of said members having an annular positioning surface formed on its periphery concentric with the axis of said shaft and of a predetermined diameter, a plurality of arcuate die segments each having a die 45 cavity in its outer convex surface and having positioning surfaces formed along its arcuate side edges for engagement with the positioning surfaces of two adjacent ones of said members, said segments being disposed in a plurality of annular rows, one such row being positioned between each adjacent pair of said members to form a cylindrical die roll, cooperating cam surface means on said members and said segments and operable by clamping force applied to said end members 50 endwise toward each other to clamp and seal the positioning surfaces of said segments against the positioning surfaces of said members, and means for applying such clamping force to said end members.

65 2. In a cast-segment type of die roll for molding cookies and like articles, the combination of a central supporting shaft, a pair of disk-like end plate members and a plurality of intermediate spider members all mounted on said central shaft concentrically therewith and in spaced relation axially of said shaft, each of said members having an outwardly facing annular positioning surface formed on its periphery concentric with the axis of said shaft and of a predetermined diameter, a plurality of arcuate die seg-

ments each having a die cavity in its outer convex surface and having inwardly facing positioning surfaces formed along its arcuate side edges for engagement with the positioning surfaces of any two adjacent ones of said members, said segments being disposed in a plurality of annular rows, one such row being positioned between each adjacent pair of said members to form a cylindrical die roll, cooperating cam surface means on said members and said segments located inwardly of said positioning surfaces operable by clamping force applied to said end members endwise toward each other to clamp and seal the positioning surfaces of said segments against the positioning surfaces of said members, and means for applying such clamping force to said end members.

3. A cast segment type of die roll for molding cookies and like articles, said die roll comprising, in combination, a central supporting shaft, a pair of disk-like end plate members and a plurality of intermediate spider members all mounted on said central shaft concentrically therewith and in spaced relation axially of said shaft, each of said members having an annular positioning surface formed on its periphery concentric with the axis of said shaft and of a predetermined diameter, a plurality of arcuate die segments each having a die cavity in its outer convex surface and having positioning surfaces formed along its arcuate side edges for engagement with the positioning surfaces of any two adjacent ones of said members, said segments being disposed in a plurality of annular rows, one such row being positioned between each adjacent pair of said members to form a cylindrical die roll, said segment members being formed with each pair of abutting end surfaces disposed at a relatively acute angle to a plane which is tangent to the segments at the line defined by the juncture of the outermost edges of said end surfaces, cooperating cam surface means on said members and said segments and operable by clamping force applied to said end members endwise toward each other to clamp and seal the positioning surfaces of said segments against the positioning surfaces of said members, and means for applying such clamping force to said end members.

4. A cast-segment type of die roll for molding 50 cookies and like articles, comprising, in combination, a central supporting shaft, a pair of disk-like end plate members and a plurality of intermediate spider members all mounted on said central shaft concentrically therewith and in 55 spaced relation axially of said shaft, each of said members having an annular positioning surface formed on its periphery concentric with the axis of said shaft and of a predetermined diameter, a plurality of arcuate die 60 segments each having a die cavity in its outer convex surface and having inwardly facing positioning surfaces formed along its arcuate side edges for engagement with the positioning surfaces of any two adjacent ones of said members, said segments being disposed in a plurality of annular rows, one such row being positioned between each adjacent pair of said members to form a cylindrical die roll, cooperating cam surface means on said members and said segments 65 and operable by clamping force applied to said end members endwise toward each other to clamp and seal the positioning surfaces of said segments against the positioning surfaces of said members, means for applying such clamping force 70 to said members, means for applying such clamping force 75

to said end members, means securing said members to said shaft for rotation with said shaft in unison, and means interlocking one of the segments of each row with one of the adjacent ones 5 of said members for the transmission of motion to each of said rows by said members.

5. A segment-type die roll for molding cookies and like articles, the combination of a central supporting shaft, a plurality of die segments each 10 constituting a segment of a cylinder and having a die cavity in its outer convex surface, means supporting said segments in spaced relation to said central shaft to form a cylindrical die roll, said segments being arranged in a plurality of 15 annular rows with the segments of each row having their end edges in abutment, said end edges being formed so that the surface of one end edge of each segment meets the outer surface of such segment at a relatively sharp acute 20 angle, and the surface of the other end edge of each segment meets the outer surface of such segment at a relatively large obtuse angle which is substantially the complement of said acute angle.

25. 6. A segment-type die roll adapted for use in a rotary cookie molding machine wherein a scraper knife bears against the surface of the die roll as it is rotated in a predetermined direction during operation of the machine, said roll comprising, in combination, a plurality of die 30 segments each constituting a segment of a cylinder and each having a die cavity in its outer convex surface, means supporting said segments to form a cylindrical die roll, said segments being arranged in a plurality of annular rows with 35 the segments of each row having their end edges in abutment, said end edges being formed so that the surface of the trailing end edge of each segment meets the outer surface of such segment

at a relatively sharp acute angle, to facilitate movement of such end joints past the engaging edge of the scraper knife.

7. A die block for use in making an assembled segment type die roll, said die block comprising 5 a rectangular segment of a cylinder, the straight edges of which segment constitute end edges of the block and the arcuate edges of which segment constitute the side edges of the block, each of said arcuate side edges of said block being 10 formed to provide a groove therein having a first side of the groove facing radially inwardly toward the axis upon which said segment is centered and forming a portion of a cylindrical surface concentric with said axis and with the arcuate outer convex surface of the block, and the other side of the groove being positioned at an acute angle to said first side of the groove.

8. A die block for use in constructing a segment type die roll, said die block comprising a 20 rectangular block of metal forming a segment and having its outer surface of an arcuate form such that a plurality of said blocks may be assembled to form a cylindrical die, the arcuate edges of said segment each having a V-shaped groove 25 formed therein spaced radially inwardly from said outer surface.

9. A die block for use in constructing a segment type die roll, said die block comprising a 30 rectangular block of metal forming a segment and having its outer surface of an arcuate form such that a plurality of said blocks may be assembled to form a cylindrical die, the arcuate edges of said segment each having a V-shaped 35 groove formed therein spaced radially inwardly from said outer surface, said groove having one side surface concentric with said outer surface.

EDWARD A. WEIDENMILLER.
